CLAIM

The ornamental design for a headlamp, as shown and described.

DESCRIPTION

FIG. 1 is a first embodiment of a front, top perspective view of a headlamp.

FIG. 2 is a left side view of the headlamp of FIG. 1.

FIG. 3 is a right side view of the headlamp of FIG. 1.

FIG. 4 is a front view of the headlamp of FIG. 1.

FIG. 5 is a rear view of the headlamp of FIG. 1.

FIG. 6 is a top view of the headlamp of FIG. 1.

FIG. 7 is a bottom view of the headlamp of FIG. 1.

FIG. 8 is a front, top perspective view of the headlamp of FIG. 1 in a connected state with environment.

FIG. 9 is a second embodiment of a front, top perspective view of a headlamp.

FIG. 10 is a left side view of the headlamp of FIG. 9.

FIG. 11 is a right side view of the headlamp of FIG. 9.

FIG. 12 is a front view of the headlamp of FIG. 9.

FIG. 13 is a rear view of the headlamp of FIG. 9.

FIG. 14 is a top view of the headlamp of FIG. 9.

FIG. 15 is a bottom view of the headlamp of FIG. 9; and, FIG. 16 is a front, top perspective view of the headlamp of FIG. 9 in a connected state with environment.

The broken lines immediately adjacent to the shaded areas depict the bounds of the claimed design, while all other broken lines are directed to environment. The broken lines form no part of the claimed design.

1 Claim, 12 Drawing Sheets
